A 34 26 54 Inventor:
George O. Irke

By Macleod, Bain & Land & She
Attorneys.

UNITED STATES PATENT OFFICE.

GEORGE P. DIKE, OF BROOKLINE, MASSACHUSETTS.

WRIST WATCH.

Application filed October 18, 1926. Serial No. 142,298.

This invention relates to wrist watches, and in general has for its object to eliminate the use of the cumbersome, inconvenient and heating strap.

Heretofore, the bracelet type of watches have been objectionable because regardless of the character of the wrist encircling member employed, it has been impossible to keep the watch and bracelet from turning about the wrist to a position out of the vision of the wearer. In order to see the watch it has been necessary for the wearer first to employ his other hand to readjust the position of the watch upon the wrist. Such operation is, of course, annoying and inconvenient and may be dangerous in the case of a person operating a motor vehicle.

An important object of the invention is to provide a wrist watch which, when clasped 20 on the wrist of the wearer, will remain in its proper position upon the top of the wrist and be, at all times, in the direct line of vision of the wearer.

Another object of the invention is to provide a wrist watch having wrist engaging arms which are normally rigid but which are formed of a material that enables them to be readily bent to the exact shape to fit the individual wearer's wrist, preferably by the 25 application of heat of a degree considerably higher than that to which the bracelet is subjected when being worn. After such shaping of the arms to the individual wearer's wrist, the watch cannot be accidentally 30 displaced from its normal and correct position upon the wrist.

A further object of the invention is to provide a wrist watch which having open wrist engaging arms, one of which is hingedly connected with the watch can be readily and quickly snapped on to the wearer's wrist, and is provided with locking means which, when locked will hold the watch securely in place, and which can be instantly unlocked 45 to permit the watch to be taken off.

Another object is to provide positive locking means which cannot be accidentally released during the usual and ordinary use of the watch.

Fig. 1 is a view in elevation of a wrist watch embodying this invention.

Fig. 2 is a plan of the same showing in dotted lines various positions which the arms may be made to assume.

Fig. 3 is a view in perspective on an en-

larged scale showing in detail a section of the watch body and the movable arm member with a single latch or locking means, the parts being disconnected.

Fig. 4 is a detail view showing another 60 form of latch or locking means.

Fig. 5 is a sectional plan view taken substantially along the lines 5—5 of Fig. 4.

Figs. 6 and 7 are respectively a plane and elevation showing another form of latch or 65 locking means, this being the preferred embodiment of my invention.

Fig. 8 is a detail cross section taken substantially along the line 8—8 of Fig. 7.

Fig. 9 is a vertical section through a portion of the watch body and movable arm, showing another type of latch or locking 70 means.

Fig. 10 is a cross sectional view taken substantially along the line 10—10, Fig. 9. 75

Fig. 11 is an elevation showing yet another form of latch or locking means.

Before explaining in detail the present improvement and mode of operation thereof, I desire to have it understood that the invention is not limited to the details of construction and arrangement of parts which are illustrated in the accompanying drawing, since the invention is capable of other embodiments, and that the phraseology 80 which I employ is for the purpose of description and not of limitation.

Referring particularly to Figs. 1 to 3 inclusive of the drawings, A represents the watch body portion, B the fixed arm, and C the movable arm, said parts together forming the wrist watch of this invention.

The watch body is formed, preferably, of metal, such, for example, as gold, silver, platinum, or the like, although it is to be 95 understood that any other suitable or desirable material may likewise be employed. The arms B and C are mainly formed, preferably, of some sort of material which is normally rigid under all ordinary degrees of 100 heat but which can be bent to assume any desired shape or configuration upon the application thereto of a degree of heat greater than that to which it is likely to be subjected in use. Several such shapes are shown in 105 dotted lines in Fig. 2. Preferably, celluloid is the particular material employed to form the arms, but, of course, any other heat bendable material may be used.

It will be observed that the arms B and C 110

are open ended, that is, have their proximate ends free and unconnected with each other, there being preferably a space between them.

The end of the watch body or case A is provided with a lug or projection 20 having a vertically extending hole 21 therethrough, and with a notch or cut-out portion 22. The face of the lug at its outer end is provided with an upward taper or cam surface 23, for a purpose to be hereinafter explained. The inner end or holder portion 24 of the movable arm C is preferably of metal and is bifurcated, providing upper and lower spaced leg portions 25 and 26, respectively, each leg being provided with aligned holes 27. The end 24 is also provided with a vertically extending recess 28, adapted to receive a pin or short shaft 29, which pin has a lateral extension or latch member 30 projecting into the space between the legs 25 and 26. The inner end of the pin 29 rests against one end of a coil spring 31 also positioned within the recess 28, the function of the spring being to maintain the pin normally in its extended or notch engaging position.

The rear face of the outer end of the watch body which is provided with the lug 20, is also provided with a notch or cut away portion 32 above and below the lug. The inner end of each leg 25 and 26 of the bifurcated inner end of the movable arm C is also notched, or cut away, as shown at 33, so as to co-operate with the notches 32 when the parts are assembled. When thus assembled, the holes 21 and 27 in the watch body and inner end of the movable arm, respectively, are in alignment and hinged together by a pivot pin 34, shown in Figs. 1 and 2.

It will be seen, therefore, that when the parts illustrated in Fig. 3 are assembled for engagement with the arm of the wearer, the projection 30 on the pin 29 is seated in the notch 22 and held therein by the pressure exerted upon it by the coil spring 31. To remove the bracelet from the arm, it is merely necessary to press the protruding end of the pin 29, which will release the latch from its engagement in the notch 22 and allow the movable arm C to swing about its pivot provided by the pin 34. When it is desired to close the bracelet, that is, to return the parts to their position of use, as shown in Fig. 2, it is simply necessary to press the arms B and C toward each other which will cause the projection 30 on the pin 29 to ride up the inclined or cam surface 23 of the lug 20, and snap into the recess 22 locking the hinge against movement.

In Fig. 4, a slightly different form of latch or locking means is illustrated. In this particular instance, the lug upon the watch body and the inner end of the movable arm are substantially like those shown in the preceding figures. The bifurcated inner

end 24 of the arm is, however, provided in its upper leg portion with a recess 35 within which is pivoted on a pin 36, a latch member 37 having a handle or actuating portion extending out of recess 35 and a latch portion extending within the recess. The lug upon the watch body is provided in its outer end with a vertically extending notch 38 (see Fig. 5) which is adapted to receive the latch portion of the latch member 32 when the hinge is locked. A spring 39 wound around the pin 36 has one end in engagement with the actuating portion of the latch 37, and normally urges the latch portion to engage the notch 38.

In Figs. 6 to 8 inclusive in which are shown my invention in its preferred form, there is shown another type of lock. In this form there are two latch members employed in lieu of a single latch as in the forms illustrated in the preceding figures. With the use of two fastening latches, the movable arm is doubly locked in position with respect to the watch body and cannot be moved unless both locks are pressed simultaneously. This lock includes two latch members 40 each having an actuating handle fitting within a recess formed in the inner end 24 of the movable arm, and each having a projecting portion. The latch members 40 are each provided with an integral lateral extension 40' terminating in a point 41 which is adapted to seat in a recess 42 one of which is formed in each face of the lug 20. Positioned also within each recess, is a coil spring 43 which engages the end of the latch and tends to force its pointed end into the space between the legs of the bifurcated inner end of the movable arm. It will be observed that the projecting ends of the latch members 40 are opposite each other and in a position where they can be easily pressed at the same time by the wearer's thumb and forefinger, so that the hinge while being doubly locked can be disengaged as easily as if only one lock were used.

Another form of locking means is illustrated in Figs. 9 and 10. In this form of the invention, the lug 20 is provided with a vertically extending hole 44, having at each end thereof, a tight fitting ring 45. Within the hole between the rings 45 is a coil spring 46. Also within said hole are positioned a pair of small studded plates 47. It will be seen that the ends of the spring 46 engage the inner face of each plate 47 and tend to force the stud on each outwardly through the perforations in the rings 45. Each leg of the bifurcated inner end 24 of the movable arm C is provided in its outer face with a recess 48. A hole 49 is also provided in each leg to connect the recess therein with the inside face of the leg, that is, with the space between the legs which receives the lug 20 on the watch body.

Within each recess 48 is provided a studded plate 50, the studs extending from opposite faces of the plate, one of which projects into the hole and is surrounded by a coil spring 51, the other projecting through the tight fitting ring 52 positioned at the outer end of the recess 48 to prevent the studded plate and spring from becoming displaced. It will be observed therefore, that the springs 51 at the inner side of each plate, tend to force the stud members 53 on one side thereof outwardly beyond the outer face of each leg, these stud members serving as operating means to force the studs on the plates 47 out of engagement with the holes 49, thereby releasing the arm C and allowing it to swing about its pivot pin 34 when it becomes necessary to remove the wrist watch from the arm of the wearer.

In Fig. 11, another form of lock is illustrated, this form being extremely simple and cheap to manufacture. In this specific form of the invention, the lug 20 is provided in its outer end or face with a slot 54. The bifurcated inner end 24 of the movable arm is provided with a longitudinally extending recess 55 adapted to receive and support a pin 56 provided with a laterally extending stud or button 57 which projects through a slot 58 formed in the outer face of the bifurcated end 24, the stud serving as actuating means for moving the pin 56. Behind the pin, within the recess 55 is a coil spring 59 which normally forces the pin 56 outwardly beyond the end of the recess 55 so that its end projects into the space between the legs 25 and 29 of the end 24, and, as shown in the drawings, engages the slot 54 in the end of the stud 20. In this manner, the movable arm will be held in its operative position until the stud 57 is moved toward the right of Fig. 11.

In order to allow the locking means or latch member to snap into its respective holding recess upon moving the arms to their operative position in each of the forms of the invention shown in Figs. 4 to 11 inclusive, tapered or cam surfaces 60 are provided adjacent each recess or notch member which is adapted to receive and hold its respective locking or latch member or members, thereby maintaining the parts of the wrist watch in operative relation. The cam surfaces 60 function in precisely the same manner as the upward tapered or cam surface 23 of the form of the invention shown in Fig. 3.

It will be understood that one or both of the arms will be bent, preferably after being subjected to heat, to the exact shape of the wearer's wrist. Since the human wrist is oval or non-circular in cross section the arms may be fitted to the wearer's wrist with some degree of freedom so that there will be no uncomfortable pressure, but still

will not turn around to the wrong side of the wrist. Also, if after being worn for a while the adjustment is either too tight or too loose and the arms do not fit the shape of the wrist perfectly, they can be further bent and adjusted. The arms can also be made of relatively slender thin pieces of celluloid which will not interfere with the movement of the wearer's wrist. The watch can be instantly put on by being clasped about the wrist, it being locked in place by the action of the snap lock and can be removed as quickly by pressing on the locked member or members, as the case may be.

What I claim is:

1. A device of the class described, comprising a body portion, a pair of open arms one of which is hinged to the body portion, and unyielding means at the hinge to hold the arms in substantially fixed clasping position.

2. In a wrist watch, a watch case, a pair of open arms one of which is hinged to the case, and a latch to lock the hinged arm adjacent the hinge.

3. In a wrist watch, a watch case and a pair of open arms which are substantially rigid at body temperatures and bendable when subjected to higher temperatures, one of said arms being hinged to the case, and means at the hinge to lock the arm in clasping position.

4. A device of the class described comprising a body, a pair of substantially rigid open arms formed of celluloid associated with the body, one of said arms being fixed to said body, the other of said arms and the body having hinge portions connected together, and means to lock the hinge portions.

5. A wrist watch comprising a watch case provided on one side with a lug, a fixed substantially rigid arm formed of heat bendable material extending from the opposite side of the case, a movable arm having a bifurcated end hingedly connected with said body lug, and locking means associated with said bifurcated end and said lug for maintaining said movable arm normally in operative relation to said case.

6. In a wrist watch, a watch case, a pair of open arms one of which is hinged to the case, and a pair of latches each adapted to lock the arm against movement about the hinge.

7. In a wrist watch, a watch case, a pair of arms, one of which is hinged to the case, and a pair of lock members the ends of which project beyond the sides of the structure adjacent the hinge, said lock members each being adapted to lock the arm against movement about the hinge pivot.

8. In a wrist watch, a watch case, a pair of arms, one thereof hinged to the case, a pair of lock members the ends of which project beyond the sides of the structure ad-

jacent the hinge, said lock members each being adapted to lock the arm against movement about the hinge pivot, and springs adapted to hold the lock members normally in locked position.

9. A device of the class described, comprising a body, a pair of substantially rigid arms extending from opposite sides of the body, each arm comprising a metallic holder, one of which being hinged to the body, and a celluloid member shaped to clasp the wrist carried by each holder, and means for holding said arms in fixed clasping position.

10. A device of the class described, comprising a main body portion, a pair of arms extending from opposite sides of the body portion, one of said arms and the body por-

tion comprising relatively movable cooperating portions, and means for releasably locking said portions together to hold the arm 20 in fixed position to clasp the wrist.

11. A device of the class described, comprising a main body portion, a pair of arms extending from opposite sides of the body portion, one of said arms being permanently 25 fixed to the body portion, the other of said arms and the body portion including relatively movable cooperating portions, and means for releasably locking said portions together to hold said last-mentioned arm in 30 fixed position to clasp the wrist.

In testimony whereof I affix my signature.

GEORGE P. DIKE.
